CLAIM

We claim the ornamental design for a convex blade grooming tool, as shown and described.

DESCRIPTION

FIG. 1 is a bottom view of the convex blade grooming tool of the present design;

FIG. 2 is a front view thereof;

FIG. 3 is a rear view thereof;

FIG. 4 is a right side view of the convex blade grooming tool, the left side view being a mirror image thereof; and,

FIG. 5 is a perspective view thereof.
